UNITED STATES PATENT OFFICE.

MOSES SHERMAN, OF ST. LOUIS, MISSOURI.

FOLDING-BED COUCH.

1,394,584.

Specification of Letters Patent. Patented Oct. 25, 1921.

Application filed May 9, 1918. Serial No. 233,470.

To all whom it may concern:

Be it known that I, MOSES SHERMAN, a citizen of the United States, residing in the city of St. Louis and State of Missouri, have 5 invented an Improvement in Folding-Bed Couches, of which the following is a specification.

This invention relates to couches and folding beds. It has for its objects to produce 10 an article of furniture of this character, combining with a couch or divan, a foldable trundling frame which may be placed thereunder, out of the way when not in use, and constituting a bed in extended condition; to 15 secure simplicity and compactness of structure and ease of operation; and to attain certain other advantages as will hereinafter more fully appear.

The invention consists in the parts and in 20 the combinations and arrangements of parts hereinafter described and set forth with particularity in the appended claims.

In the accompanying drawing illustrating 25 a practical embodiment of the invention,-- Figure 1 is a view with the end panel of the divan removed and the back frame thereof in section, and showing the seat and back in end elevation, and also showing the foldable trundling bed-frame in end elevation as 30 folded and placed out of the way under the seat;

Fig. 2 is a detail view on an enlarged scale, of the trundling frame as folded and in section;

Fig. 3 is a fragmentary detail view of the 35 frame, showing the relative positions of certain parts thereof in its opened condition; and

Fig. 4 is a fragmentary view showing the 40 stop for limiting the outward position of the frame.

Referring now to the drawing, the numeral 1 indicates the end panel and 2 the back panel of the box-frame of the divan. 45 Attached to the end panels, as by bolts 3, is the seat-frame 4 having the usual upholstered cushion 5 thereon. Pivoted on the end panels, as at 6, is the upholstered back 7 which is spaced from the back panel 2 and 50 rests with its lower end portion against stop members 8 on the seat-frame 4, thereby providing a compartment 9 for the storage of bed clothing, access being had to said compartment by swinging the back 7 upward as 55 shown by the dotted lines in Fig. 1.

Beneath the seat-frame 4 is a foldable

trundling bed-frame comprising a panel or front board 10 serving as a removable finishing panel for the box-frame of the divan when the foldable trundling frame is placed 60 under the seat and as a support for said frame in its extended condition.

On the inner face of said panel 10, near the ends thereof, are parallel angle members 11 to which are pivotally attached hinged 65 members 12, also of angle section. Attached to said hinge members 12 is a supporting frame comprising a T-shape end frame and an angle-shape cross member 13, the stem of the T 14 and the cross-head 15 thereof being 70 also of angle section, and said stem and head being braced by the diagonal connecting member 16.

Pivoted to the cross-heads 15, as at 17, are 75 the side rails 18 of one of the folding sections of the bed-frame, said rails being preferably of angle section as are substantially all the other members of the frame. The opposite end portions of the rails 18 are pivotally attached, as at 19, to a supporting frame 80 comprising the end members 20 and cross connecting members 21 and 22, the one, 21, being of angle section, and the other, 22, being a flat bar.

On the free ends of the members 20 are 85 angle-pieces 23 which straddle the upstanding flanges of the side rails 24 of a base-frame whose outer end portions are riveted to the lower end portions of the members 11 on the panel 10, while their inner end portions are attached to a cross member 25.

In the collapsed or folded condition of the frames, the pieces 23 rest on said upstanding flanges of the rails 24, while the rails 18 rest with their horizontal flanges on the horizontal flanges of the members 20 (see Figs. 1 and 2), thereby affording a support. In the opened condition of the frames, as shown by the dotted lines in Fig. 1, the pieces 23 are engaged in notches 26 provided therefor 90 in said upstanding flanges of the rails 24.

Pivoted on the cross-heads 15 of the T-frames, as at 27, is a second folding frame comprising the side rails 28 and the end member 29. The frames 18 and 28, which 105 are hinged on the opposite ends of the cross-head of the T-frames constitute two opposed bed frames. The rails 28 have pivoted thereon, as at 30, folding leg members 31, and to said leg members, as at 32, the ends of connecting bars 33 are pivoted, the opposite ends of said bars being pivotally attached to the 110

stems 14 of the T-frames, as at 34. By this arrangement, the leg members 31 lie alongside of the vertical flanges of the rails 28 in the folded condition of the frames (see Figs. 5 1 and 2), and by providing stop-pieces 35, preferably of angle section, on the rails 28, so that one of their legs projects beyond the outer face of the rail to be engaged by said folding leg members 31, the frame 28 when 10 folded is supported by the connecting bars 33. By this arrangement, also, the leg members 31 assume a vertical position at right angles to the rails 28 and are steadied by the bars 33, when the frame is in opened condition.

To limit the outward position of the base-frame, the panels 1 are provided with suitable stops for engagement by the end member 25 of said base frame. As shown, these 20 stops may comprise bracket members 36 having offset end portions 37 projecting into the path of said end member 25; and, obviously, to facilitate moving the frame, the rails 28 are provided with suitable casters or rollers 25 38 which rest on the floor the same as the casters 39 which are provided on the box-frame of the divan proper. It is also obvious that the base-frame may, if desired, be mounted to slide on some suitable supporting guide-way on the end panels 1.

From the foregoing it is noted that the invention comprehends a structure which may be used as an ordinary divan or couch, and it may be readily converted into a full-size bed. Any suitable foldable bed-bottom fabric may be conveniently supported from the horizontal flanges of the respective frame members 15, 18 and 28, and the pad or mattress 40 (see Fig. 1) may be readily 40 folded therewith.

To open the trundling section of the device, it is only necessary to first move out the base to its full extent and then swing up the upper folding frame and thence outward and downward, causing the T-frame to swing up to the vertical position, as best shown in Fig. 3, during which time the inner end of the lower folding frame will be lifted until the pieces 23 are brought into engagement with the notched portions 26 of the rails 24 of the base-frame. As the upper folding frame is brought down to horizontal position, the leg members 31, through the pivotal link connections 33, right themselves 50 to vertical position so as to rest on the floor to support the foot of the bed; and as the base-frame is held from further outward movement by the stops 37 which are engaged by the end member 25, the inner folding frame cannot collapse as long as the supporting frame is engaged with the

notches 26 of the base-frame, but will tend to abut the seat 4 of the divan proper.

To fold back or collapse the frames for replacement under the divan seat, it is only 65 necessary to raise the outer folding frame, and raise the inner frame sufficiently to release its supporting frame from the notches 26 of the rails 24 and to permit the T-frame to move back to horizontal position, and 70 then lower the whole structure until it is supported on the base-frame as hereinbefore described.

Obviously, the structure admits of considerable modification without departing from 75 the spirit of the invention as defined by the appended claims, and it is, therefore, not limited to that shown in the drawings.

What is claimed is:

1. In a foldable bed-frame comprising a 80 base-frame, a supporting frame hinged thereon, and two opposed bed-frames hinged on said supporting frame, one of said opposed bed-frames having foldable supporting legs adapted to support the same in 85 opened position, a folding supporting frame hinged on the other of said bed-frames, said folding supporting frame being adapted to rest on said base-frame and support said bed-frame in collapsed position and being adapted to engage said base-frame to support said bed-frame in opened position, and means on said base-frame adapted to coöperate with the free end of said folding supporting frame for preventing accidental disengagement of said folding supporting frame from said base-frame when said bed-frame is in 90 opened position.

2. In a device of the character described, a divan or the like, and a foldable trundle 100 bed-frame movable in collapsed position under the seat of said divan and operating in open position to constitute a bed with said seat, said trundle bed-frame comprising a base-frame provided with notched portions, a T-frame hinged on said base-frame, and two bed-frames hinged respectively on the opposite ends of the cross-head of said T-frame, one of said bed-frames having foldable legs adapted to support said frame in 105 open position, and a supporting frame pivotally connected to the other of said bed-frames, said supporting frame being adapted to rest on said base-frame and support said bed-frame in collapsed position and being adapted to engage the notched portions 110 of said base-frame and rigidly support said bed-frame in opened position.

Signed at St. Louis, Missouri, this third day of May, 1918.

MOSES SHERMAN.
